UNITED STATES PATENT OFFICE.

WALTER G. HADSALL, OF DETROIT, MICHIGAN.

LOCKING DEVICE.

Application filed April 28, 1926. Serial No. 105,105.

This invention relates to improvements in locking devices, and refers more particularly to locking devices adapted, when in locked position, to prevent rotation of one member 5 around a second member which passes through the device.

It is, among other things, an object of this invention to provide a locking device that may be applied to prevent the removal of a 10 nut from a bolt which passes through a wheel and rim lug thereby holding the rim in position, by anyone who does not possess a key. At the present time the theft of rims and 15 tires is an altogether too common practice, and this invention aims to provide a simple and effective means of stopping these thefts.

Another object of the invention is to provide a locking device wherein the latch is, when in locked position on a nut or bolt 20 head, entirely enclosed, so that there is no danger of its being forced back into unlocked position by direct leverage. Moreover the arrangement of the latch on the operating mechanism is such that even if the 25 nut or bolthead were removed downward pressure on the latch could not move it without first breaking the mechanism.

A further object of the invention is to provide a locking device which can be 30 cheaply manufactured, and quickly and easily applied to any existing type of wheel and rim without any alteration being made to those parts.

Having thus briefly outlined the major 35 purposes of the invention I will now proceed to describe the preferred embodiment thereof, as applied either to an ordinary wooden wheel and rim lug, or to a disc wheel and rim lug, with the aid of the accompanying drawings.

In the drawings:

Figure 1 illustrates the invention as applied to an ordinary wooden wheel and rim lug, and so positioned on the wheel as to be 45 nearly opposite the valve stem.

Figure 2 is a section on the line 2—2 of Figure 1.

Figure 3 is a view of the locking device looking at the side against which the rim 50 lug bears.

Figure 4 is a section on the line 4—4 of Figure 2.

Figure 5 is a section on the line 5—5 of Figure 4.

55 Figures 6 and 7 are sections on the lines 6—6 and 7—7 of Figure 2.

Figure 8 is a view showing the application of the invention to a disc wheel and rim lug.

Figure 9 is a section on the line 9—9 of 60 Figure 8, and

Figure 10 is a section on the line 10—10 of Figure 9.

Referring to Figures 1, 2 and 6, 1 designates an ordinary wooden wheel, 2 a rim, 3 65 a rim lug, and 4 a bolt to hold the lug in position. In Figures 8 and 9, 1^a designates a disc wheel having a rim 2^a thereon, 3^a is a lug usually integral with the rim, and 4^a is a bolt by which the rim lug and wheel are 70 secured one to the other.

5 and 5^a respectively indicate two forms of lock casing which are similar except for variations in contour on the surface 24 which is intended to bear against the lug 3 or 3^a. 75

In the casing is a cylindrical opening 6 having a plug 7 therein which is held against axial movement by a locating pin 8 which engages a slot 9 in the periphery of the plug. This slot extends preferably around substantially one half the circumference of the plug, so that the pin 8 also limits its rotary movement. In the side of the casing and radial with the cylindrical opening tumbler extensions 10 are provided, the ends of which are 85 held in contact with the tumbler pins 11 in the plug by springs 12. 13 indicates plugs driven into the casing after the tumbler pins, tumbler extensions, and springs have been placed in position. The plug 7 is also provided with a key slot 14 for a key 15. 13^a is a plug to hold the locating pin 8.

In the recess 16 in the casing, and at right angles to the cylindrical opening 6, a latch 17 is arranged across the lower end of which 95 is a transverse groove 18. The end of the plug 7 has an eccentric projection 19 thereon which engages this groove so that as the plug is turned the latch is moved up or down in its recess. Moreover it will also be noted 100 that the projection is so positioned with regard to the slot 9 that the limits of the turning movement of the plug are reached when the projection is at substantially its highest and lowest points. 16^a indicates another 105 plug by which the end of the recess is usually closed after the latch 17 has been inserted.

Through the casing a circular hole 20 is provided for the passage of the bolt 4 or 4^a. This hole is of sufficient size to permit the 110 smaller head 22 of the nut 23 rotating therein. It will be noted that the axis of the bolt

is at right angles to the direction of movement of the latch 17, and that the latter, when in raised position, projects into the side of the hole in such a manner as to form a stop for one of the flats of the head 22 of the nut 23 to prevent the latter from turning. The surface 24 of the casing is so shaped intermediately of its vertical sides 25 as to form a bearing surface for the rim lug 3, or 3^a.

The bolt 4, when in position through the wheel, is prevented from turning by the square 31 contiguous to the bolt head and integral therewith which engages a corresponding recess in the wheel. Though obviously in different forms of wheels various known methods of holding the bolt against rotation are employed. For instance in the case of the bolt 4^a the latter is so positioned with regard to the flange 2^b of the wheel rim 2^a that the latter prevents the bolt from turning. The rim lug 3, or 3^a, and the locking device are placed on the bolt and the nut 23 is tightened until one of the flats of the head 22 is parallel with the direction of travel of the latch 17. The key 15 is then inserted in its slot 14 in the plug and the latter turned thereby raising the latch into locked position. The nut is then positively held against rotation until the latch has been lowered.

In order to simplify the setting of the nut I generally make the flats on the outer portion of the nut parallel with the flats on the head 22.

After the key has been removed from the plug the end of the cylindrical opening is covered by any desired form of closure member 26 to exclude the dust and dirt.

I prefer to case harden the exposed portion of the nut 23 so that it will not get out of shape particularly when attempts are made to tamper with it. Though when it is left soft it is practically impossible to remove the rim from the wheel when the device is locked, because the head 22 integral with the nut is within the circular opening 20 where it would require considerable time and effort to cut that portion of the nut away even after the outer head had been severed.

In both Figures 1 and 8 the locking device is shown almost opposite the valve stem 35, for it is found that when locked in that position it is practically impossible to remove the rim without ruining the tire, so the use of one such locking device affords ample protection for each rim and tire.

While in the foregoing the invention has been described and shown applied to a tire and rim, it is however understood that it may be put to many other varied uses. Moreover the construction herein described is subject to such modifications and altera-

tions as fall within the scope of the appended claims.

What I claim as my invention and desire to secure by Letters Patent is:

1. In a locking device, the combination of a casing having an opening therethrough, a member having an opening therethrough bearing against one surface of said casing, a bolt through both of said openings, a nut having a smaller multi-sided head integral therewith in threaded engagement with said bolt, said smaller head being adapted to turn in said opening in said casing, a latch slideable in said casing adapted to bear against said smaller head and prevent rotation of said nut, and means for moving said latch.

2. In a locking device, the combination of a casing having a larger opening therethrough, a member having a smaller opening therethrough bearing against said casing, a bolt through both of said openings, a nut larger than the opening in said casing having a smaller multi-sided head integral therewith, said nut being in threaded engagement with said bolt, said smaller multi-sided head being adapted to turn in the opening in said casing, a latch adapted to slide in said casing transversely of said opening and to engage one of the flats on said multi-sided head and hold it against rotation, means for moving said latch and for positively holding said latch against movement.

3. In a wheel rim lock, the combination with a rim lug having a hole therethrough and an offset end, of a casing so shaped as to bear against said lug and said offset portion, said casing having an opening therethrough registering with said rim lug hole, a bolt passing through said hole and said opening, a nut having a multi-sided head adapted to rotate in said casing and in threaded engagement with said bolt, and a latch slideable in said casing and adapted to hold said nut against rotation.

4. In a wheel rim lock, the combination with a rim lug having a hole therethrough and an inner offset end, of a casing so shaped as to bear against said lug and said offset end, said casing having an opening therethrough registering with said rim lug hole, a bolt passing through said hole and said opening, a nut in threaded engagement with said bolt and having a multi-sided head adapted to rotate in said casing, a latch slideable in said casing and adapted to hold said nut against rotation, said latch having a transverse groove therein, a plug in said casing having a keyslot therein, and an eccentric pin on one end of said plug taking into said latch groove so that said latch is moved by the rotation of said plug.

WALTER G. HADSALL.
